WILLIAM B. ELLIOTT AND WILLIAM O'BLENIS, OF WESTFIELD, NEW JERSEY,
ASSIGNORS, BY MESNE ASSIGNMENTS, TO BURKE ELECTRIC COMPANY.

CONSTANT-CURRENT ARC-WELDING SYSTEM.

1,412,463.

Specification of Letters Patent. Patented Apr. 11, 1922.

Application filed March 14, 1918. Serial No. 222,277.

To all whom it may concern:

Be it known that we, WILLIAM B. ELLIOTT and WILLIAM O'BLENIS, citizens of the United States, both residing at Westfield, 5 county of Union, State of New Jersey, have invented new and useful Improvements in Constant-Current Arc-Welding Systems, of which the following is a specification.

This invention relates to a system for 10 welding, brazing or otherwise treating metals by means of the electric arc.

Where the arc is fed from a constant potential, it is very unstable. This has been overcome to some extent by placing resistance in circuit with the arc, but this is a wasteful proceeding. A much more efficient method is to vary the voltage impressed on the arc electrode according to the resistance of the arc. For this purpose, the 20 generator supplying the voltage may be so regulated that the field excitation, and consequently the voltage will be lowered when the current increases, due to the lowering of the resistance of the arc circuit as by 25 decrease in the resistance of the arc. Conversely the excitation of the generator should be increased with an increase in the resistance of the arc circuit.

The present invention has for its main 30 object the provision of improved means for effecting the regulation of the voltage in the arc circuit, which means is especially adapted to regulate the voltage in the manner as just described and which is also 35 suitable for regulation of the arc circuit in other respects.

Other and ancillary objects of the invention will appear hereinafter.

The accompanying drawing, which illustrates the invention, is a diagrammatic showing of apparatus and connections of a system embodying the invention.

Referring to the drawing, the arc is adapted to be formed between the work 1 and an electrode 2, and is supplied with current by means of a direct current generator including the armature 3, the series field 4 and the field 5. One terminal of the armature 3 is connected through the 45 series field 4 and the series field 6 of an exciter to be further referred to hereinafter, with the electrode 2. The other terminal of the generator is connected with the work 1. The field 5 is supplied with 50 current by a compound wound exciter com-

prising the armature 7, the shunt field 8 and the series field 6. The series field may be provided with an adjustable shunt 9 for varying the proportion of the arc current flowing through the series field 6 of the exciter. One terminal of the armature 7 is connected through a rheostat 10 with one terminal of the field 5 of the generator armature, while the other terminal of the exciter armature 7 is connected with the other terminal of the field 5. The rheostat 10 is for the purpose of initial adjustment of the field current in winding 5. The main generator has its fields arranged differentially, that is, the fields 4 and 5 are opposed to each other so that as the series field strengthens, the total field excitation of the generator will be reduced.

The exciter being compound wound, the shunt and series fields 8 and 6 act in conjunction so that a strengthening of the series field strengthens the resultant field on the exciter.

With the electrodes 1 and 2 separated and no current flowing, the voltage of the main generator supplying the arc will be that due to its field 5, which is excited by the exciter armature 7 subjected to the excitation of the shunt field 8 only. The series fields 4 and 6 have no effect as no current is flowing. Under these conditions, the voltage is such that when the electrodes 1 and 2 are touched together to strike the arc there will not be an undue rush of current. As soon as current flows in the 90 arc circuit, however, the current through the series field 6 of the exciter, will cause an increase in the field of the exciter with a consequent increase in the voltage, with a 95 resultant increase in current through the field 5, which tends to increase the strength of the field of the main generator and therefore its voltage. The voltage therefore impressed on the arc circuit is increased over the low voltage which exists at the time the electrodes are brought together, but a 100 great rush of current is prevented by reason of the fact that the bucking series field 4 which carries the working current, decreases the main generator voltage. Normal working conditions having thus been established with the arc drawn between the electrodes, the bucking action of the series field 4 will 105 tend to reduce the voltage in the arc circuit whenever there is an increase in current due 110

to a decrease in the arc circuit resistance and conversely it will tend to prevent decrease of current in the arc circuit upon an increase of its resistance. The result is that the arc current may be maintained substantially constant and the arc rendered stable.

An adjustable shunt 11 may also be provided for regulating the series field 4.

10 While the invention has been illustrated in what is considered its best application, it may have other embodiments without departing from its spirit, and is not therefore, limited to the structure shown in the drawing.

15 What we claim is—

1. The combination of a circuit having a load device varying widely in resistance, a generator supplying said load device, said 20 generator comprising a main field winding, an auxiliary source of electromotive force supplying said main field winding, and means responsive to conditions in said circuit for regulating said source, said generator also comprising a series field winding opposed to said main field winding.

2. The combination of a circuit having

a load device varying widely in resistance, a generator supplying said load device, said generator comprising a main field winding, 30 and an auxiliary generator supplying said main field winding, said auxiliary generator having a shunt field winding and a field winding connected in series in said circuit, said first named generator also having a series field winding opposed to said main field winding.

3. The combination of a circuit having a load device varying widely in resistance, a generator supplying said load device, said generator comprising a main field winding, 35 and an auxiliary generator supplying said main field winding, said auxiliary generator having a shunt field winding and a field winding connected in series in said circuit 40 and said last two named windings having an additive effect, said first named generator having a series field winding opposed to said main field winding.

In testimony whereof we have signed 50 this specification this 23d day of February, 1918.

WILLIAM B. ELLIOTT.
WILLIAM O'BLENIS.
